UNITED STATES PATENT OFFICE.

WILLIAM A. DARRAH, OF CHICAGO, ILLINOIS.

DESIGN FOR A LOUD-SPEAKER HORN.

Application filed June 13, 1924. Serial No. 9,868. Term of patent 14 years.

To all whom it may concern:

Be it known that I, WILLIAM A. DARRAH, a citizen of the United States, residing at Chicago, county of Cook, and State of Illinois, have invented a new, original, and ornamental Design for Loud-Speaker Horn, of which the following is the specification, reference being had to the accompanying drawing, forming a part thereof.

Figure I shows a perspective view looking at the horn partly from the front and

partly from the side. Figure II shows a plan view of one form of my device while Figure III shows a view of the side elevation of my device.

The horn is preferably made of glazed porcelain or similar ceramic material.

I claim:—

The ornamental design for a loud speaker horn as shown.

WILLIAM A. DARRAH.
